METHOD AND APPARATUS FOR THE PREVENTION OF SOUING IN DIESEL ENGINES
 Henry U. Wisniowski, Ottawa, Ontario, Canada, assignor to Canadian Patents and Development Limited, Ottawa, Ontario, Canada, a corporation of Canada
 Filed July 22, 1964, Ser. No. 384,407
 1 Claim. (Cl. 123—32)

This invention relates to a method and apparatus for the prevention of "souping" in diesel engines.

During idling of diesel engines for long periods of time, a phenomenon known as "souping" occurs. This souping is evidenced by the appearance of black sludge which

2

between the disc and the top of the piston. The spray holes of the fuel injector 7 inject a spray 13 of fuel into the cavity. These spray holes 12 are directed outwardly and downwardly. It has been found that best results in preventing souping are obtained when the fuel sprays impinge partially on the disc 1.

The discs used should be made of high temperature-resistant metal. They must be capable of withstanding the temperatures of up to 1100° C. encountered in the combustion chambers. Tests have shown that discs made of Nichrome or Inconel are quite suitable.

The following experimental results were obtained on a 12-cylinder locomotive diesel engine. An anti-souping disc was placed in the No. 1 cylinder as indicated.

Anti-souping device in No. 1 cylinder	Fuel	First cylinder started to soup after—	Cylinder No. 1 started to soup after—	Total Hours of Idling
Flat annular	Pembina Crude Oil	7.75 hrs.	48.5 hrs.	51
Full disc	do	7 hrs.	53 hrs.	66
Disc with $\frac{1}{4}$ in. dia. hole	do	6.75 hrs.	62.75 hrs.	73
Do	Standard Diesel Fuel	22.25 hrs.	100.25 hrs.	115

comes out from the exhaust system of the engine. Souping is most pronounced in locomotive diesel engines which are left idling for long periods of time. Diesel engines for other services are normally not left idling long enough to show souping.

Souping is manifested externally by a bluish-grey smoke of a fog type issuing from the exhaust. If the engine is examined, unburned or partially unburned fuel will be found in the cylinders and in the exhaust system.

Souping has occurred in locomotive service with standard diesel fuel but when crude oils were tested as substitute fuels, the souping phenomenon was found to be much aggravated. In its heavy form souping is troublesome and greatly increases the fire danger of the installation and surroundings. It is also suspected that it accelerates the deterioration of the lubricating oil and increases the wear of the engine.

It is an object of the present invention to provide a method of eliminating or reducing the occurrence of souping in diesel engines especially those on locomotive service.

It is another object of the invention to provide a means of reducing souping which is reasonably inexpensive, easily adaptable to present engines, and which is fixed in position and, therefore, not subject to dynamic forces which might tend to destroy it.

In drawings which illustrate embodiments of the invention,

FIGURE 1 shows the preferred form of the invention attached to the cylinder head of a diesel engine,

FIGURE 2 shows a cross section of the device of FIGURE 1.

Referring to FIGURE 1 a cylinder head 4 of a diesel engine with inlet and exhaust ports 5 and valves 4A is shown. A flat circular metallic disc 1 having a central aperture 6 is fixed to the cylinder head and positioned from it by means of legs 2. Studs 3, which screw into holes drilled in the head, hold the disc securely in place.

FIGURE 2 shows a cross-section of a cylinder head 4 and a piston 11. Disc 1 should be located away from the surface of cylinder head 4 so that the temperature of the disc will be higher (closer to that of the gas in the cavity) than that of the cylinder head itself. For mechanical reasons sufficient clearance should be allowed

It can be readily seen from these results that the use of the anti-souping devices greatly increases the length of time that a diesel engine can be idled before souping becomes evident. This improvement is obtained even with heavy crude oils and by using the devices, one of the drawbacks to using this type of fuel is almost eliminated.

The above results were found to be reproducible and it can be expected with reasonable probability that provided the injectors are in good condition, the start of visible souping with the anti-souping discs will not occur before 50 hours of idling on crude oils. In the case of standard diesel fuels the souping-free time with the discs is at least 100 hours.

Investigations conducted on the test engine and combustion rig showed that souping is caused to a great extent by the contact of injected fuel with the relatively cold walls of the combustion chambers resulting in partial burning or no burning of a part of this fuel.

The anti-souping discs when placed in the combustion chamber are heated by combustion gases to the temperature much above the temperature of the walls of the chamber. The injected sprays of fuel either strike the hot discs or pass close to it by which they are heated and burnt before they reach the cold walls of the combustion chamber. In this way, the souping problem is greatly alleviated.

What is claimed is:

In a diesel engine of the type having a cylinder, a piston in the cylinder, a cylinder head forming a combustion chamber above said piston, and a fuel nozzle located in said head, constructed to discharge separate conical spray patterns at widely divergent angles generally radially from the nozzle and through said combustion chamber formed between the crown of said piston and said cylinder head; the improvement comprising a generally flat disk located in said combustion chamber arranged in a plane transverse to an axis bisecting the divergent angle of the spray pattern, means for supporting said disk spaced from the piston and cylinder head with the central portion of said disk exposed only to the gases in said chamber and with only the periphery of said disk disposed to intercept a portion of the conical sprays from said nozzle which approach the adjacent head of the piston, said means pro-

viding sufficient spacing to form a barrier to heat transfer from the disk to maintain disk temperature above ignition temperature at engine idle speeds.
